UNITED STATES PATENT OFFICE.

BENJAMIN F. MOONEY, OF FINDLAY, OHIO.

DESIGN FOR A DUET PIANO-BENCH.

41,901.

Specification for Design.

Patented Nov. 7, 1911.

Application filed May 31, 1911. Serial No. 630,491. Term of patent 14 years.

To all whom it may concern:

Be it known that I, BENJAMIN F. MOONEY, a citizen of the United States, residing at Findlay, in the county of Hancock and State of Ohio, have invented a new, original, and ornamental Design for a Duet Piano-Bench, of which the following is a specification, reference being had to the accompanying drawings, forming a part thereof.

The figure is a perspective view of a duet piano bench, showing my design.

I claim:

The ornamental design for a duet piano bench, as shown.

BENJAMIN F. MOONEY.

Witnesses:

C. A. STOCKTON,
W. F. OPP.
